WAVE LENGTH MODULATION

Lowell E. Norton, Princeton Junction, N. J., assignor to Radio Corporation of America, a corporation of Delaware

Application August 25, 1945, Serial No. 612,684

14 Claims. (Cl. 332—23)

1

One of the earliest and best known phase and frequency modulation methods involves phase displacing two portions of wave energy of carrier wave frequency, differentially amplitude modulating the phase displaced carrier wave energies, combining the same and selecting from the combined energies the carrier components and filtering out or in some other manner eliminating from the used output the undesired components of which there are many. Examples of this type of phase or frequency modulation are illustrated in Crosby U. S. Patent #2,081,577, dated May 25, 1937; and Crosby U. S. Patent #2,165,229, dated July 11, 1939.

In systems of this type the phase displacement obtainable between the two portions is limited.

An object of my present invention is to provide a system of this general type wherein the frequencies of the phase displaced portions are multiplied like amounts before they are differentially modulated to thereby produce initially a large amount of modulation to extend greatly the range of ultimate phase or frequency modulation.

I realize that multiplication of two timing modulated carrier energy portions and recombination of the same in frequency or phase modulation systems is known in the art. An example of such an arrangement is shown in Goldstine U. S. Patent #2,335,934, dated December 7, 1943. However, in Goldstine the carrier energy portions are of like phase when differentially modulated and then the resulting modulations are multiplied unequal amounts in the two channels and supplied to a converter wherein they are combined to derive as the main or primary output carrier components which supply the frequency or phase modulated output.

My present improved method and means differs from systems of this type in that the carrier portions are phase displaced, multiplied in frequency like amounts to greatly enhance the relative phase displacement and extend the range of phase or frequency modulation which is then accomplished by differentially modulating the phase displaced portions.

In systems of this type known heretofore, as stated above, when the phase displaced currents are modulated the modulated output includes a large number of components which are unuseable. These components except the two fundamentals are not only unuseable, but create distortion and in some cases even cancel out power in the fundamentals which is desired as useful output.

An object of my present invention is to provide a method of the type outlined generally above,

wherein the entire system and in particular the tube stages therein are so arranged, selected and operated that in the modulator outputs, which are combined in parallel, all unwanted modulation product terms or modulation components except the two fundamental carriers cancel to zero. The advantages of such a system will be obvious to one skilled in the art. Such a system eliminates the need of filters in the modulator's output to remove the undesired components and select and pass along only the desired component.

In the Goldstine patent referred to hereinbefore, the arrangement is such that in the modulator outputs the components other than the useful components are readily eliminated, so that only useful output is supplied for signalling purposes. The primary modulation components not to be used in Goldstine's output are so widely removed in the frequency spectrum from the modulation components put to use that there should be little or no trouble in eliminating the unwanted components from the energy used for signalling purposes. However, to accomplish this result in Goldstine, the two modulators must be substantially exactly similar, or an exceedingly large number of modulation components closely related in the frequency spectrum to the two fundamentals will be produced. In fact, the outputs of the two modulators, in case the same were dissimilar in operation, could well be represented by a Fourier series and these components would result in distortion which would be difficult to eliminate, even by the use of filters.

In my improved system, the tubes all operate on linear portions of the curves, and the operation is such that the modulation components other than those to be put to use occur in pairs of opposite sign so that they must cancel to leave only the useful fundamental carrying the signal modulations. In the system described adjustment and operation is not difficult since the two channels are identical; and since the required phase relations are only 180 degree phase reversals, it is not necessary to maintain and monitor critical phase relations. Of most importance, the two modulators need not operate exactly similarly because all that is necessary is that they operate about in the same manner so that after cancellation of the opposed pairs of side bands the fundamentals which are to be used will be about equal in magnitude and will add in the parallel output.

In one embodiment of my system the modulators are single ended and this system supplies an output which is substantially pure phase or frequency modulation, without distortion and with-

out the need of filters in all cases except where a very wide frequency deviation is to be accomplished. In such cases as, for example, in case the deviation frequency approaches the carrier frequency, an extremely large number of components appear in the modulation output close to the useful fundamental. To overcome this defect I provide an embodiment wherein the modulators are differential instead of single ended. In the differential modulator outputs then, as stated above, the components appear in pairs to cancel to zero, leaving only the fundamental carriers which are combined in parallel and supplied to the load.

The above advantages and others, and the manner in which they are attained will be apparent from the description which follows.

In this description reference is made to the attached drawings wherein Fig. 1 illustrates mainly by rectangles the essential elements or units of a phase or frequency modulation system arranged in accordance with my invention.

Fig. 2 illustrates details of one embodiment of my modulation system, while

Fig. 3 illustrates a modification of the arrangement of Fig. 2 to be used where the deviation frequency is very high.

In the drawings, Fig. 1, 10 is a source of oscillations of constant wave carrier wave frequency having a frequency of say $F=W/2\pi$. The source 10 may be conventional and may comprise if desired a stabilized oscillator such as a crystal oscillator and/or frequency multipliers. The output of the oscillator 10 is supplied to two coupling and isolating and/or amplifying stages T₁ and T₂. One of the stages is supplied substantially directly from 10 while the other stage is supplied by way of a transmission line L having a time delay angle represented for convenience by the Greek letter ψ . The stages T₁ and T₂ prevent coupling of the two channels by way of the source 10 or circuits therein. These stages also permit adjustment of the gain through the channels so that the gain through T₁, for example, is about equal or substantially equal to the gain through T₂ and its delay line. The delay line L may comprise an artificial line or network, a transmission line, or a wave guide.

The stages T₁ and T₂ may comprise amplifier tubes of substantially conventional design having their input electrodes excited by phase displaced oscillatory energy from 10. The potential applied to the input circuit of T₁ is

$$e=E(1+m \sin \omega t) \quad (1)$$

and that applied to the input circuit of T₂ is

$$e_1=E[1+m_1 \sin (\omega t+\psi)] \quad (2)$$

where ψ is the delay angle due to the line L, E is the peak or maximum alternating current voltage for $m=1$ and m is the modulation factor. In these equations and those which follow E represents peak or maximum alternating voltage from the oscillator 10 for $m=1$ at frequency $f=\omega/2\pi$. The factor m represents all variations from this peak initial voltage including in later equations variations caused by modulation. Subscripts are used with m to denote different modulation factors when the same may be used, like subscripts being used to denote the same modulation factors where such must be used. For example, in the Equations 1 and 2 different modulation factors may be used. For convenience and to simplify the description and facilitate understanding of the invention E has been so chosen that the vari-

ations m are always positive, that is, in the anode-cathode circuits, take place about a base line sufficiently above zero potential as to be positive at all times. This will be referred to again later. It is also convenient to make the modulation factor m_1 equal the modulation factor m . In practice it would be substantially equal since both currents come from the same source 10, and the tubes are alike.

The output potential from tube T₁ is then

$$e_2=kE(1+m \sin \omega t) \quad (3)$$

and the output potential from T₂ is

$$e_3=k_1 E[1+m \sin (\omega t+\psi)] \quad (4)$$

In these equations k represents the gain of stage tube T₁ and k_1 represents the gain of tube stage T₂.

It is convenient to make $k=k_1$ which is done by adjusting the gains of the stages and then e₃ becomes

$$e_3=kE[1+m \sin (\omega t+\psi)] \quad (5)$$

The output of stages T₁ and T₂ is supplied to the first and third grids of tubes in the next stages of the two channels as will be seen by reference to Fig. 2. A modulating or mixing or converting action takes place in these stages and they have been referred to as modulators since modulation product terms appear in the output.

The potential $e_2=kE(1+m \sin \omega t)$ is applied to say the third grid 14 of M₁ through a coupling condenser 16. A voltage e_2' of opposite phase equal to $kE(1-m \sin \omega t)$ is applied to the first grid 18 by way of a coupling condenser 20. The last voltage may be provided in any one of various known ways. For example, the stage T₁ tube may supply phase displaced output by coupling to an anode impedance and to a cathode impedance, or the tube anode may feed the primary winding of a transformer having a differential secondary winding. In considering these voltages it is to be kept in mind that the average voltage say E is above zero an amount such that it does not swing negative.

In like manner a voltage

$$e_3=kE[1+m \sin (\omega t+\psi)]$$

is applied to the third grid 24 of the tube in stage M₂ by a coupling condenser 26 while a phase reversed voltage $e_3'=kE[1-m \sin (\omega t+\psi)]$ is applied by the coupling condenser 28 to the first grid 30 of this tube.

The modulators M₁ and M₂ must be operated on the linear portions of their characteristics and this is assured by the use of proper grid biasing resistors 34 and 36, proper plate source 38, appropriate plate resistors 40 and 42, proper screen grid sources 44 and 46, and cathode return resistors 50 and 52 shunted by R. F. bypass condensers. A common source of direct current potential may replace the several sources which are shown separate for convenience and to simplify the connections. In furtherance of the need of linear amplification it is preferable to use tubes of the type 6SA7 or 6L7, if the amplification is done at very low level (with possibility of final large linear amplification). At higher level amplification one may use tubes known in the art as types 802, 803, 804 and 807, all operated with input potentials applied to control grid and screen grid. For this operation the modulation factor can not be made too large (probably always less than 0.5) or the interaction between grids will be serious.

The requirement is the same in all cases; i. e.

tubes in which the grid-to-grid transconductance is small. This is met in the 6SA7 and 6L7 by extra shielding or screening grids. The types 802, 837, 804, 803 do not have the extra screening grids so they must be operated at smaller modulation factor.

It would be possible to omit modulators (mixers) M_1 and M_2 and apply the outputs of T_1 and T_2 to the modulator tubes T_3 and T_4 directly. However, the useful phase shift will only be ψ . It is possible to make ψ become 2ψ by one frequency multiplication. One frequency multiplication is used in the description which follows although obviously more multiplication may be used.

As stated above, the potentials applied to the grids 14 and 18 of tube M_1 are respectively

$$e_2 = kE(1 + m \sin \omega t) \quad (6) \text{ also (3)}$$

and

$$e_2' = kE(1 - m \sin \omega t) \quad (7)$$

The potentials applied to the grids 24 and 30 of tube M_2 are respectively

$$e_3 = kE[1 + m \sin(\omega t + \psi)] \quad (8) \text{ also (5)}$$

and

$$e_3' = kE[1 - m \sin(\omega t + \psi)] \quad (9)$$

As a consequence, the output of M_1 is

$$e_4 = k_4 E \left(1 - m^2 \sin^2 \omega t \right) = k_4 E \left[\left(1 - \frac{m^2}{2} \right) + \frac{m^2}{2} \cos 2\omega t \right] \quad (10)$$

and the output of M_2 is

$$e_5 = k_5 E \left[1 - m^2 \sin^2(\omega t + \psi) \right] = k_5 E \left[\left(1 - \frac{m^2}{2} \right) + \frac{m^2}{2} \cos(2\omega t + 2\psi) \right] \quad (11)$$

It is convenient to make $k_5 = k_4$ so that

$$e_5 = k_4 E \left[\left(1 - \frac{m^2}{2} \right) + \frac{m^2}{2} \cos(2\omega t + 2\psi) \right] \quad (12)$$

To make k_5 equal k_4 the gains of stages M_1 and M_2 are properly adjusted by relative adjustment of the value of the grid bias resistances 34 and 36 or of the potential sources, etc., as is well known in the radio art.

The outputs e_4 (Equation 10) and e_5 (Equation 12) appear at leads 56 and 60 respectively Figs. 1 and 2, and are fed to the stages T_3 and T_4 wherein variation of the R. F. voltages by the signals is accomplished.

If desired more stages of frequency multiplication may be added to make 2ψ become 4ψ or larger.

The stages wherein the signal modulation is applied to the carrier to relatively or differentially modulate the amplitudes of the phase displaced voltages e_4 (Equation 10) and e_5 (Equation 11) are shown at T_3 and T_4 in Figs. 1 and 2. As shown in Fig. 2 these stages each comprise a multi-grid tube (preferably one of the type listed above). The tube of stage T_3 has a cathode bias resistance 62, a grid bias resistance 64, a plate source 66, a plate impedance 68, a screen grid source 70, and resistance 72. The stage T_4 comprises a similar tube with similar connections and sources to which reference numerals corresponding to those used in stage T_3 have been applied. These tube stages like the tubes M_1 and M_2 are operated on the linear portions of their characteristic curves by the use of potentials and resistances of proper value. The gains of the

tubes are also set to provide outputs which are substantially of equal magnitude.

The anodes of tubes M_1 and M_2 are coupled by condensers 84 and 86 to the control grids 71 and 81 of tubes T_3 and T_4 . The third grids 79 and 89 of the tubes T_3 and T_4 are excited differentially by modulation currents or potentials from the modulation source 87 by way of modulation coupling condensers 90 and 92.

If now modulating or biasing potential, from source 87,

$$e_6 = E_6[1 + m_6 f(t)] \quad (13)$$

where $f(t)$ is the modulation frequency term which is time dependent and where $f(t) < 1$ since, as usual, $m_6 \max = 1$ and the R. F. voltage

$$e_4 = k_4 E \left[\left(1 - \frac{m^2}{2} \right) + \frac{m^2}{2} \cos 2\omega t \right] \quad (14) \text{ also (10)}$$

are applied respectively to the grids 79 and 71 of T_3 , the output of T_3 will be

$$e_7 = k_7 E \left[\left(1 - \frac{m^2}{2} \right) [1 + m_6 f(t)] + \frac{m^2}{2} [1 + m_6 f(t)] \cos 2\omega t \right] \quad (15)$$

If the period of $f(t)$ is long as compared to

$$\frac{\pi}{\omega}$$

a frequency selective circuit may be placed in the output circuit of T_3 to reject the potential

$$(k_7 E) 1 - \frac{m^2}{2} m_6 f(t)$$

The filtering required is almost inherent in the circuit unless special pains are taken to prevent it. The period of the modulation $f(t)$ is likely to be at audio rate, or at least very low as compared to that of the high frequency output. Therefore, if impedances 68 and 78 in the anode-cathode

circuits of tubes T_3 and T_4 respectively, have proper impedances over the range of high frequencies used, the same impedances are likely to have (or can be made to have) approximately zero impedance at the low modulation frequencies and only useful output will result.

If the modulation frequency is low as compared to the carrier frequency, impedances 68, 78 may easily be made to have a high impedance at carrier frequency and approximately zero impedance at the low modulation frequency. This condition is the normal condition.

If the period of $f(t)$ is not long as compared to

$$\frac{\pi}{\omega}$$

then it is only necessary to change the modulator T_3 of Fig. 2 to the balanced modulator T_3' shown in Fig. 3, and to add to the output of T_3' the original potential

$$k_8 E \frac{m^2}{2} \cos 2\omega t.$$

To change to the balanced modulator arrangement of Fig. 3 the output of M_1 is arranged to supply differential or pushpull R. F. excitation to the stage T_3' . The arrangement of Fig. 3 then may be as illustrated in Figs. 1 and 2 as far as the source 10 and stages T_1 and T_2 and the inputs to stages M_1 and M_2 are concerned. The output of the tubes of stages M_1 and M_2 may each include the primary winding of a transformer having a differential secondary winding feeding the following stages T_3' and T_4' respectively. Other means such as phase inversion as described hereinbefore in connection with stages

T_1 and T_2 for converting from single ended to double ended translation may be used. In the balanced modulators T_3' and T_4' reference numerals corresponding to those used in describing T_3 and T_4 have been used on the electrodes and circuit elements for one tube in each modulator. Corresponding reference numerals primed have been used on the electrodes and circuit elements of the remaining tube in each balanced modulator.

The control grids 11, 11' of T_3' are supplied with potentials $e_6, e_6' = E_6[1 + m_6 f(t)]$. The third grids 19, 19' of T_3' are supplied with potentials

$$e_4, e_4' = k_4 E \left[\left(1 - \frac{m^2}{2} \right) \pm \frac{m^2}{2} \cos 2\omega t \right] \quad (10)$$

The output potential of the balanced modulator T_3' is obviously

$$e_8 = k_8 E \left[1 - \frac{m^2}{2} + \frac{m^2}{2} m_6 f(t) \cos 2\omega t \right] \quad (16)$$

For convenience make $k_8 = k_7$ by relatively adjusting the gains of T_3 and T_4 . If the original potential

$$k_8 E \frac{m}{2} \cos 2\omega t$$

is added to the output potential e_8 the result is the same as that for e_7 in Eq. 15 but with the troublesome, unwanted term

$$\left(1 - \frac{m^2}{2} \right) [1 + m_6 f(t)]$$

removed, all without any restriction on the relation between $f(t)$ and $2\omega t$, and without use of a frequency $f(t)$.

Correspondingly, if $f(t) < \omega t$ then modulator T_4 is also as shown in Fig. 2. The input potentials supplied to grids 81 and 89 of T_4 are respectively $e_6' = E_6[1 - m_6 f(t)]$ and

$$e_5 = k_4 E \left[\left(1 - \frac{m^2}{2} \right) + \frac{m^2}{2} \cos (2\omega t + 2\psi) \right] \quad (11)$$

The output of T_4 is

$$e_9 = k_9 E \left\{ \left(1 - \frac{m^2}{2} \right) [1 - m_6 f(t)] + \frac{m^2}{2} [1 - m_6 f(t)] \cos (2\omega t + 2\psi) \right\} \quad (18)$$

It is convenient to make $k_9 = k_8$ again by adjustment of the gain of the tubes.

Here, as in the output of T_3 (Fig. 2) a frequency selective circuit in the output of tube T_4 rejects potential

$$k_9 E \left[1 - \frac{m^2}{2} m_6 f(t) \right]$$

If desired, and where the deviation is large, say of the order of the carrier frequency, the balanced modulator T_4' , which is the same in connections and operation as that shown for T_3' , may be substituted for the modulator T_4 , as described hereinbefore.

The control potentials applied to grids 81 and 81' are

$$e_6', e_6 = E_6[1 \mp m_6 f(t)]$$

and the radio frequency potentials on grids 89 and 89' are

$$e_5, e_5' = k_4 E \left[\left(1 - \frac{m^2}{2} \right) \pm \frac{m^2}{2} \cos (2\omega t + 2\psi) \right] \quad (70)$$

The output of T_4 is

$$e_{10} = k_{10} E \left[1 - \frac{m^2}{2} - \frac{m^2 m_6}{2} f(t) \cos (2\omega t + 2\psi) \right] \quad (19)$$

For convenience make $k_{10} = k_9$. If, as before, an output (original) potential

$$k_{10} E \frac{m^2}{2} \cos (2\omega t + 2\psi)$$

is added to e_{10} the result is the same as the potential e_9 in Eq. 18 but with the low frequency term

$$k_9 E \left(1 - \frac{m^2}{2} \right) m_6 f(t)$$

eliminated without use of a low frequency rejection circuit.

The original potentials

$$k_8 E \frac{m}{2} \cos 2\omega t \text{ and } k_{10} E \frac{m^2}{2} \cos (2\omega t + 2\psi)$$

may be added to the outputs of T_3' and T_4' respectively as illustrated in Figure 1. Output including the component

$$k_8 E \frac{m}{2} \cos 2\omega t$$

is taken from stage T_1 and applied through de-coupling resistance R_4 to the output combining resistance R_3 . Output including the component

$$k_{10} E \frac{m^2}{2} \cos (2\omega t + 2\psi)$$

is taken from stage T_2 and fed over resistance R_5 to the combining resistance R_3 . It is not actually necessary to add these potentials. The circuit will operate without them. By so doing I may then use the same algebra in Equations 20, 21, and 22 for the two cases of tubes T_3 , T_4 , and T_3' , T_4' . If the two extra potentials are not added, a very similar result to Equations 20, 21, and 22 appears, but with an unimportant difference due to the different resultant modulation factor. The connections including R_4 and R_5 used to supply the said original potentials are used only when balanced modulator stages T_3' and T_4' are used as in Fig. 3. In the other embodiments these circuits are removed.

In Fig. 2 the outputs of tubes T_3 and T_4 are coupled by coupling condensers 100 and 110 and resistances R_1 and R_2 to the common load resistance R_3 , while in Fig. 3 the anodes of the differentially excited tubes in each stage T_3' and T_4' are tied in parallel and then coupled in parallel to load resistance R_3 by coupling condensers 100 and 110 and resistances R_1 and R_2 . The outputs of T_3 and T_4 of Figure 1 are combined in parallel (subtracted), in such a manner that the fundamental carrier and its modulations only are left. The outputs of T_3' and T_4' are each combined in parallel or added algebraically so that all components except the fundamental carrier and its modulation components add to zero and disappear from the output without the use of filters. The useful components appear in the load R_3 . The values of R_1 and R_2 are made equal and much greater than the value of R_3 to prevent reactive coupling of the output of T_4 or T_4' to T_3 or T_3' and vice versa.

The outputs of T_3 and T_4 , as of T_3' and T_4' , are combined in the circuit composed of

$$R_1 = R_2 \gg R_3$$

to prevent interaction. The combined output is

$$e_{11} = k_{11} E \left\{ 2 \left(1 - \frac{m^2}{2} \right) + \frac{m^2}{2} [1 + m_6 f(t)] \cos 2\omega t + \right.$$

$$\left. \frac{m^2}{2} [1 - m_6 f(t)] \cos (2\omega t + 2\psi) \right\} \quad (20)$$

As usual

$$-1 \leq m_6 \leq 1 = \text{constant}$$

and the numerical value $f(t)$ is also

$$-1 \leq f(t) \leq 1$$

and variable with time. Rewriting Equation 20

$$e_{11} = k_{11}E \left[2 \left(1 - \frac{m^2}{2} \right) + \frac{m^2}{2} \sqrt{4 + 2[m_6 f(t)]^2 (1 - \cos 2\psi)} \sin \left[2\omega t + \tan^{-1} \left(\frac{2}{[1 - m_6 f(t)]} \sin 2\psi - \tan \psi \right) \right] \right] \quad (21)$$

or its equivalent

$$e_{11} = k_{11}E \left[2 \left(1 - \frac{m^2}{2} \right) + \frac{m^2}{2} \sqrt{4 + 2[m_6 f(t)]^2 (1 - \cos 2\psi)} \cos \left[2\omega t + \tan^{-1} \left(\frac{[1 - m_6 f(t)] \sin 2\psi}{[1 + m_6 f(t)] + [1 - m_6 f(t)] \cos 2\psi} \right) \right] \right] \quad (22)$$

In either case the incremental instantaneous frequency is equal to the time rate of change of phase angle. Designating the instantaneous incremental frequency by F_1

$$F_1 = \frac{d}{dt} \left\{ \tan^{-1} \left(\frac{[1 - m_6 f(t)] \sin 2\psi}{[1 + m_6 f(t)] + [1 - m_6 f(t)] \cos 2\psi} \right) \right\} \quad (23)$$

from Equation 23

$$F_1 = \frac{-\sin 2\psi \left\{ [1 + m_6 f(t)] + \cos 2\psi - m_6 f(t) \cos 2\psi \right\} \frac{d}{dt} [m_6 f(t)] + [1 - m_6 f(t)] \left[1 - \frac{d}{dt} (m_6 f(t)) \cos 2\psi \right]}{[1 + m_6 f(t)]^2 + 2[1 - m_6 f(t)]^2 \cos 2\psi + [1 - m_6 f(t)]^2 (\cos^2 2\psi + \sin^2 2\psi)} \quad (24)$$

or

$$F_1 = -\frac{m_6 \sin 2\psi \frac{d}{dt} [f(t)]}{1 + [m_6 f(t)]^2 + (1 - [m_6 f(t)]^2) \cos 2\psi} \quad (24)$$

From Equation 24 it is evident that the instantaneous incremental frequency varies directly with the time rate of change

$$\frac{d}{dt} [f(t)]$$

Also, if $\cos 2\psi$ is chosen so as not to depart too greatly from unity, then

$$F_1 \approx -\frac{m_6}{2} \sin 2\psi \frac{d}{dt} [f(t)] \quad (25)$$

and the modulation is linear. The same approximation yields the final simplified result

$$F_1 \approx -m_6 \psi \frac{d}{dt} [f(t)] \quad (26)$$

If half T_3' and half T_4' (tubes removed) become unoperative the circuit will still operate but reverts to the circuit of Fig. 2 provided that the tubes were removed "on the same half." If tubes were removed on one side of T_3' and the opposite side of T_4' the circuit would again revert to a form of the circuit of Fig. 2 but in this case the variable phase angle (which is a function of the modulating potential) would be different.

If the circuit of Fig. 2, or the circuit of Fig. 3 with tubes pulled "on the same side" gives an output across resistance R_3 of the form

$$e = E \left\{ 1 + m \sin \left[2\omega t + \tan^{-1} \left(\frac{1}{\sin 2\omega t} \right) \right] \right\}$$

then pulling out tubes "on opposite sides" of T_3' and T_4' will give an output potential across R_3 of the form

$$e = E \left\{ 1 + m \sin \left[2\omega t + \tan^{-1} \left(\frac{1}{\sin 2\omega t} \right) \right] \right\}$$

The only difference is that the magnitude of the variable phase angle is different.

It is noted that in Fig. 2 the modulation from source 87 is applied to third grids 79 and 89 of tubes T_3 and T_4 and the radio voltage is applied to the first grids 71 and 81 whereas in Fig. 3 the modulation is applied to the first grids and the radio voltage is applied to the third grids of tubes T_3' and T_4' . Both methods of operation are correct and the results are identical.

What I claim is:

1. The method of producing alternating current modulated as to timing in accordance with signals which includes these steps, generating alternating current of carrier wave frequency

$$e_{11} = k_{11}E \left[2 \left(1 - \frac{m^2}{2} \right) + \frac{m^2}{2} \sqrt{4 + 2[m_6 f(t)]^2 (1 - \cos 2\psi)} \cos \left[2\omega t + \tan^{-1} \left(\frac{[1 - m_6 f(t)] \sin 2\psi}{[1 + m_6 f(t)] + [1 - m_6 f(t)] \cos 2\psi} \right) \right] \right] \quad (22)$$

which is of substantially fixed frequency, separating the alternating current into two portions of about like intensity, phase displacing the alternating current of one portion relative to the alternating current of the other portion, deriving from said one and said other current portions phase opposed currents multiplied in frequency by like amounts, mixing the phase opposed cur-

rents derived from the one and other current portions, selecting the sum or double frequency currents resulting from each mixing step differentially amplitude modulating the selected currents, and so adding the resultant alternating currents that all components except the fundamental carrier and its phase or frequency modulation components cancel.

2. The method of producing alternating current modulated as to timing in accordance with signals which includes these steps, separating alternating current of substantially fixed frequency into two portions of about like intensity, phase displacing the alternating current of one portion relative to the alternating current of the other portion, deriving from each of said one and other portions corresponding but phase opposed currents, beating the phase opposed currents derived from said one and said other portions to obtain from each thereof resultant current, differentially amplitude modulating the resultant currents, and combining the modulated currents in parallel.

3. The method of producing alternating current modulated as to timing in accordance with signals which includes these steps, generating alternating current of carrier wave frequency which is of substantially fixed frequency, separating the alternating current into first and second portions of about like intensity, phase displacing the alternating current of one portion relative to the alternating current of the other portion, deriving from each of said one and other portions corresponding but phase opposed currents, combining the phase opposed currents derived from said one and other portions to derive resultant current from each thereof, differentially amplitude modulating the resultant currents and combining the modulated currents.

4. The method of producing carrier current modulated as to timing in accordance with sig-

11

signals which includes these steps, producing alternating current of substantially fixed carrier frequency, separating the alternating current into two portions of about equal intensity, relatively phase displacing the alternating currents of the two portions, deriving from each portion two corresponding portions of opposed polarity, beating the two corresponding portions of opposed polarity derived from each of said two portions to derive resultant currents from each beating process, multiplying the frequency of the resultant currents, differentially amplitude modulating the resulting frequency multiplied currents and adding the modulation energy algebraically.

15 5. The method of producing carrier current modulated as to timing in accordance with signals which includes these steps, producing alternating current of substantially fixed carrier frequency, separating the alternating current into first and second portions of about equal intensity, relatively phase displacing the alternating currents of the two portions, deriving from each of said first and second portions two corresponding portions of opposed polarity, beating the two corresponding portions derived from each of said first and second portions to derive resultant currents from each beating process, deriving from each of said resultant currents a pair of currents of opposed phase, differentially amplitude modulating the currents of the opposed pairs and adding the resultant modulation currents.

20 6. The method of producing carrier current modulated as to timing in accordance with signals which includes these steps, separating alternating current of substantially fixed frequency, into first and second portions of about equal intensity, relatively phase displacing the alternating currents of the first and second portions, deriving from each of said first and second portions two corresponding portions of opposed polarity, beating, one against the other, the two corresponding portions derived from each of said first and second portions to derive resultant currents of multiplied frequency from each beating process, deriving from each of said resultant currents a pair of currents of opposed phase, differentially amplitude modulating the currents of the opposed pairs and adding the resultant currents for signalling purposes.

25 7. The method of producing carrier current modulated as to timing in accordance with signals which includes these steps, generating oscillatory energy of substantially fixed frequency, separating the oscillatory energy into two portions, relatively phase displacing the oscillatory energies of the two portions deriving from each of said relatively phased displaced energy portions other energies of opposed phase, mixing and multiplying the frequency of the oscillatory energies of each of the two opposed energy portions like amounts, selecting from the multiplied energies the sum or double frequency energies resulting from each mixing step, differentially amplitude modulating the last-mentioned portions of frequency multiplied oscillatory energy and adding the resulting energies algebraically.

30 8. In combination a source of oscillatory energy of fixed frequency, two frequency multiplier tubes having like factors of multiplication, a coupling between said source and one tube, a coupling between said source and the other tube, means in one of said couplings for displacing the phase of the oscillatory energy passed thereby, a first modulator stage comprising two tubes coupled differentially to one of said multiplier tubes, a

12

second modulator stage comprising two tubes coupled differentially to the other multiplier tube, a common load impedance coupling the output of said modulator tubes in parallel, and a source of modulating potential coupled to the modulator tubes.

35 9. In combination a source of oscillatory energy of fixed frequency, two electron discharge devices, a coupling between said source and one device, a coupling between said source and the other device, means in one of said couplings for displacing the phase of the oscillatory energy passed thereby, a first two tube modulating stage having an input coupled differentially to one of said devices, a second two tube modulator stage having an input coupled differentially to the other of said devices, a common load impedance coupling the outputs of all of said modulator tubes in parallel, and a source of modulating potential differentially coupled to the modulator tubes in each stage.

40 10. In a timing modulation system in combination, a source of alternating current of fixed frequency, two converter tubes operating on the linear parts of the characteristic curves, two couplings between said source and one tube, a current phase reverser in one of said couplings, two couplings between said source and the other tube, a phase shifter in both of said last two couplings and a current phase reverser in one of said last two couplings, a first modulator stage coupled to the output of one of said converter tubes, a second modulator stage coupled to the output of the other converter tube, a common load impedance coupling the output of said modulator stages in parallel, and a source of modulating potential differentially coupled to the modulator stages.

45 11. In a timing modulation system in combination, a source of alternating current of fixed frequency, two converter tubes operating on the linear parts of their characteristic curves, two couplings between said source and one tube, a current phase reverser in one of said couplings, two couplings between said source and the other tube, a phase shifter in both of said last two couplings and a current phase reverser in one of said last two couplings, a first pair of modulator tubes coupled differentially to the output of one said converter tubes, a second pair of modulator tubes coupled differentially to the output of the other converter tube, a common load impedance coupling the outputs of said modulator tubes in parallel, and a source of modulating potential differentially coupled to the modulator tubes of each pair.

50 12. In a timing modulation system in combination, a source of alternating current of fixed frequency, two converter and current frequency multiplier tubes operating on the linear parts of their characteristic curves, said frequency multiplier tubes being operated to multiply the frequency of the currents like amounts, two couplings between said source and one tube, a current phase reverser in one of said couplings, two couplings between said source and the other tube, a phase shifter in both of said last two couplings and a current phase reverser in one of said last two couplings, a first modulator stage coupled to the output of one of said converter tubes, a second modulator stage coupled to the output of the other converter tube, a common load impedance coupling the output of said modulator stages in parallel, and a source of modulating potential differentially coupled to the modulator stages.

55 13. In a signalling system, a source of oscilla-

13

tory system of fixed frequency, a pair of linear amplifiers having input and output electrodes, couplings between said source and the input electrodes of each of said amplifiers, a phase shifter in one of said couplings, a pair of frequency multiplier tubes of the multi-grid type, a push-pull coupling between the output electrodes of one of the amplifiers and two grids of one of the multiplier tubes, a push-pull coupling between the output electrodes of the other amplifier and two of the grids of the other multiplier tube, a source of modulating potential, a first pair of modulator tubes of the multi-grid type, a push-pull coupling between the output electrodes of one of said multiplier tubes and corresponding grids of said first pair of modulator tubes, a push-pull coupling between said source of modulating potential and corresponding grids in said first pair of modulator tubes, a pull second pair of modulator tubes of the multi-grid type, a push-pull coupling between the output of other of said multiplier tubes and corresponding grids in the tubes of said second pair of modulator tubes, a push-pull coupling between said source of modulating potential and corresponding grids of said second pair of modulator tubes, a load impedance and means coupling the output electrodes of the tubes of each pair of modulator tubes in parallel to said load impedance.

14. In a signalling system, a source of oscillatory energy of fixed frequency, a pair of linear amplifiers having input and output electrodes, couplings between said source and the input

14

electrodes of each of said amplifiers, a phase shifter in one of said couplings, a pair of frequency multiplier tubes of the multi-grid type, a push-pull coupling between the output electrodes of one of the amplifiers and two grids of one of the multiplier tubes, a push-pull coupling between the output electrodes of the other amplifier and two of the grids of the other multiplier tube, a source of modulating potential, a pair of modulator tubes of the multi-grid type, couplings between the output electrodes of the respective multiplier tubes and corresponding grids of the tubes of said pair of modulator tubes, a push-pull coupling between said source of modulating potentials and other corresponding grids of the tubes of said pair of modulator tubes, a load impedance and means coupling the output electrodes of the tubes of said pair of modulator tubes in parallel to said load impedance.
